CASING AND CONTROLS FOR A DUAL TELEPHONE COMMUNICATOR

Anthony A. Ardolino, Miami, Fla., assignor to Howard
Research and Development Corporation, Miami, Fla.

Filed May 26, 1971, Ser. No. 147,297

Term of patent 14 years

Int. Cl. D14—03

U.S. Cl. D26—14

FIG. 1

FIG. 2

FIG. 3

FIG. 4

FIG. 5

FIG. 6

FIG. 1 is a plan view of a casing and controls for a dual telephone communicator, showing my new design.

FIG. 2 is a front elevation thereof.

FIG. 3 is a rear elevation thereof.

FIG. 4 is a right hand elevation thereof.

FIG. 5 is a bottom plan view thereof.

FIG. 6 is a perspective view thereof.

The side not shown is a mirror image of that shown in FIG. 4.

I claim:

The ornamental design for casing and controls for a dual telephone communicator, as shown and described.
